COMPRESSION IGNITION ENGINE

Robert P. Ramsey, Philadelphia, Pa., assignor to
 The National Supply Co. of Delaware, Toledo,
 Ohio, a corporation of Delaware

Application September 24, 1936, Serial No. 102,379

2 Claims. (Cl. 123—32)

This invention relates to internal combustion engines of the compression ignition type utilizing a solid injection spray nozzle and is particularly directed to the construction of such an engine so as to control the combustion therein.

The primary object of the invention is the provision of means to accomplish the most advantageous combustion of the fuel injected into a compression ignition engine.

Another object of the invention is the provision of a means for controlling the combustion of fuel, portions of which assume different physical states upon injection, which consists in providing for each portion air in the conditions most desirable for the advantageous burning of that portion.

Another object of the invention is the provision of an apparatus, wherein main and auxiliary combustion chambers are provided and so disposed with relation to a fuel injection nozzle that portions of the fuel spray in different physical conditions are fed to the two chambers, and the air in the respective chambers is in the proper condition of turbulence required to burn advantageously the part of the fuel in that chamber.

More specifically an object of the invention is to inject a fuel stream through a chamber containing relatively quiescent air, into which the highly atomized envelope of the stream distributes itself, while the dense core of the stream passes into a chamber containing rapidly swirling air with which it is mixed.

Other objects and advantages of the invention will become apparent as the description proceeds, reference being had to the accompanying drawings, in which—

Figure 1 is a fragmentary sectional view with parts in full, of an engine embodying the present invention, the section being taken on line 1—1 of Fig. 2; Fig. 2 is a section on line 2—2 of Fig. 1; Fig. 3 is a somewhat diagrammatic sectional view of the combustion chambers showing a longitudinal section through a typical fuel nozzle and spray; Fig. 4 is an enlarged view of a nozzle tip; Fig. 5 is a cross-sectional view through a typical fuel spray, and Fig. 6 is a typical indicator diagram taken during operation of an engine constructed in accordance with the present invention.

Referring to the drawings, the present invention is shown in connection with an engine having a cylinder 4 surrounded by a water jacket 2 through substantially its entire working length. A piston 3 works in the bore of the cylinder in the usual manner.

The present invention is particularly directed to the cylinder head part of the engine, which includes a body 4 bolted to the cylinder block and spaced therefrom by suitable gaskets 5. A fuel injection nozzle 6 is seated in one side of the head and is disposed to discharge fuel directly into a main combustion chamber 7. The fuel injection nozzle is preferably of the pintle type and includes a reciprocating plunger 20 having a conical seat 21 adjacent its forward end, which is adapted to cooperate with a congruous conical surface 22 formed in the body of the nozzle. The nozzle opening 23 communicates with the interior of the nozzle and is made slightly larger than the pintle 24, which projects through the opening. The pintle is formed with reversely conical surfaces 25 and 26 at its tip which control to a certain extent the angularity of the spray discharge. The plunger 20 is backed by a spring 21, which controls the pressure required to open the nozzle, so that fuel may discharge into the cylinder head. Fuel is introduced into the nozzle through a passage 16 under a predetermined pressure and this pressure, exerted on the forward end of the plunger 20, lifts the conical valve 21 from its seat so that fuel may pass through the opening 23 around the pintle 24.

The main combustion chamber 7 is open at its bottom to the cylinder and is shaped to present a minimum of surface for the dissipation of heat and to form a space suited to permit the outer spray envelope of the fuel jet from the nozzle 6 to distribute itself most thoroughly and mingle with the air in the chamber. To this end, the chamber is preferably made to flare from the injection nozzle so that the conical spray discharge will not impinge on the side walls of the chamber. The dimension of this main combustion chamber in the line axially of the fuel injection nozzle 6 is dictated by the consideration that the atomized portion, or spray envelope, of the injected jet of fuel penetrates the compressed gas in the chamber only a certain distance for a given injection and compression pressure. It is desirable that the spray envelope of the jet be confined within the walls of the main combustion chamber for a purpose which will presently become apparent.

It has been found that the discharge from a nozzle of the pintle type is divided into two parts which differ widely in their physical characteristics. As shown in Figs. 3 and 4, the spray pattern shows a core C of fuel which is in substantially solid, coarsely atomized, form surrounded by an envelope D of highly atomized fuel parti-

cles. The outer envelope D, due to its fine atomization, penetrates only a relatively small distance into the heavy compressed atmosphere in the cylinder head, and also, due to its fine atomization, 5 is adapted to burn quickly and smoothly in a quiescent volume of air. On the other hand, the substantially liquid central core C of the fuel spray will penetrate a much greater distance in the heavy atmosphere and, before it can be efficiently 10 burned, must be broken up to be intermingled with air particles required for combustion.

While the invention has been disclosed in connection with a nozzle of the pintle type, it should be appreciated that any other nozzle which 15 discharges a spray having similar characteristics of core and envelope may be used.

In order to burn the coarse central core C of the fuel stream, an auxiliary combustion chamber 9 is provided at the opposite side of the main 20 combustion chamber 7 to the injection nozzle. The chamber 9 is cylindrical in form and its axis is preferably parallel to the axis of the working cylinder 1. The auxiliary combustion chamber 9 communicates with the main combustion chamber 7 through a passage 10 which is axially aligned with the fuel injection nozzle 6 and which may be belled, or slightly enlarged at its opening 25 into the combustion chamber 7 to an extent such that it includes the heavy liquid part of the injected fuel spray. The opening of the passage 10 into the auxiliary combustion chamber 9 is disposed tangentially of the cylindrical wall of the latter, so that a rapid swirl of air in the auxiliary combustion chamber is set up when air 30 is forced into the main chamber and thence into the auxiliary chamber by an upward movement of the piston 3 on the compression stroke of the engine. The swirling will continue during the injection of the heavy central core of the fuel 35 spray into the chamber, and causes the core to be broken up and thoroughly intermingled with the air in the auxiliary chamber.

A suitable air inlet valve 15 is seated in the roof of the main combustion chamber 7. Air 45 introduced through this valve scavenges the burned gases from both combustion chambers 7 and 9 on the intake stroke of the piston and also serves to reduce the temperature of the valve seat and valve head, thus promoting longer life 50 of these parts.

An exhaust valve 16 is seated in the cylinder head immediately overlying the piston space.

While the engine starts rapidly from cold, it may be desirable to provide emergency means to 55 temporarily increase the compression ratio of the engine when it becomes necessary to start under extreme conditions, as when the engine has been standing for some time in extremely cold weather. For this reason a plug valve 14 is placed in the passage 10 to interrupt communication between the main and auxiliary combustion chambers during the starting period. The valve may be operated by any suitable means, manual or automatic. It will be appreciated that 60 when this valve is closed the compression ratio of the engine is increased by the extent that the available compression space is diminished. Obviously the increase in compression causes an increase in resulting air temperature which, in turn, promotes rapid cold starting.

The operation of the present engine is such that the division of the fuel spray is made in accordance with its physical conditions. In the example shown, the finely atomized portion 75 remains in the main chamber and the relatively

solid core is shot on through the main chamber into the auxiliary chamber. This is advantageous since the physical condition of the spray determines the type of chamber which is best suited to burn the fuel. For a finely atomized body of fuel dispersed in air, quiescence is highly desirable, since the air and fuel particles are in ideal condition for combustion. On the other hand, a body of fuel which is in a substantially liquid condition must be mixed with air before 10 it will burn, and requires turbulent air to break it up, mix with it, and produce the proper conditions for efficient combustion. Also it is highly desirable that there be in each chamber sufficient air for burning the fuel under the conditions existing in that chamber. If, for example, 70% to 75% of the fuel is finely atomized in the main chamber and a core comprising 30% or 25% of the fuel passes on into the auxiliary chamber, the amount of air in the respective chambers 15 should be proportioned in approximately the same ratio, although extra air for thorough combustion may be provided where the conditions of combustion require it.

In the quiescent chamber 7 the highly atomized 20 part of the fuel will burn smoothly and quickly with a very slight ignition lag. The fuel sensitivity of the engine is determined largely by the dimensions of the main combustion chamber 7, since this chamber must have an axial dimension 25 large enough so that the fuel envelope mixes with the air and no appreciable impingement of the atomized fuel occurs on the wall opposite the injection nozzle. Thus, the atomized fuel must have a chance to mingle with and be stopped 30 by the quiescent air before it impinges upon the wall of the chamber, since fuel that impinges upon and clings to the wall in the quiescent main chamber does not become properly mixed with the air and does not burn with the fuel mixture 35 in the chamber. The size and shape of the chamber should be adjusted sufficiently to the degree of compression, shape of nozzle tip and injection pressure to prevent any substantial impingement upon the walls of the main combustion chamber in order to best effect the objects 40 of this invention. This same consideration determines the starting qualities of the engine, since obviously, if the fuel impinges against the cold wall of the combustion chamber, it will not 45 burn and start the engine. The dimension from the nozzle tip to the nearest adjacent metallic surface is sufficiently great so that all of the fuel injected in an atomized condition mingles with the air and burns to start the engine. It has 50 been found in practice that in an engine in which the compression pressure is approximately 380 pounds, and fuel is injected from a pintle type nozzle under a pressure of 1600 pounds per square inch that a distance of nearly 3 inches is most 55 advantageous to completely stop the spray envelope of the jet.

The dimension from the nozzle tip to the 60 oriifice of the auxiliary chamber also physically establishes a lag between the combustion of the atomized fuel in the quiescent chamber and the combustion of the liquid core, since the latter must travel entirely across the main chamber before it can enter the turbulent chamber, and since it must circulate in the turbulent chamber 65 for a period of time before it can become sufficiently broken up to be in condition for combustion. The liquid core can actually travel through a burning mass in the main chamber 7 and remain 70 in a substantially liquid condition having only a 75

small outer layer burned during its passage. The major part of the core will still enter the auxiliary chamber as a coarse spray. In the operation of the engine, it has been found that the finely atomized fuel envelope burns almost as soon as it is injected into the chamber 1, and an indicator card shows a consequent moderate rate of progressive pressure rise. The central heavy core moves across the open combustion space and enters the auxiliary combustion chamber which is at such a distance from the point of injection of the fuel that the core does not burn until later in the cycle after the introduction and burning of the outer spray envelope in the open chamber. The core is taken up in the rotary swirl of air in the auxiliary combustion chamber and is vaporized and burned, setting up a very high pressure inside the auxiliary chamber. This pressure is choked by the passage 21 so that it cannot act directly on the piston, but rather is throttled by the passage 21, into the open chamber to act on the piston head as it recedes on the pressure stroke of the engine. The dimension of the main combustion chamber between the fuel injection nozzle and the orifice of the passage 21 is so great that as the gases issue from the chamber 9 they will not impinge on and burn the tip of the nozzle.

The indicator cards, an example of which is shown in Fig. 5, show that the burning of the initially atomized fuel is practically complete before the pressure in the auxiliary chamber begins to exert its force on the piston, so that as this pressure is released from the auxiliary combustion chamber a second distinct pressure rise in the main chamber takes place.

While the invention has been disclosed in connection with a specific illustration of one application thereof, it will be understood that variations may be made while retaining essential features of this invention.

As indicated, one of the important features is the provision of a relatively quiescent body of air into which the fuel jet is directed and into which all of the fuel that can be sufficiently atomized is distributed, so that full advantage is taken of the atomization effected by the injection, while the relatively solid core of the fuel jet moves on into a turbulent mass of air that effects its atomization. It is preferable that these two

bodies of air shall be in about the same proportion to each other as are the two portions of fuel that enter the respective bodies of air.

Other changes within the scope of the appended claims may be made without departing from the invention.

Having thus described my invention, what I claim as new, and desire to secure by United States Letters Patent, is:

1. In an internal combustion engine having a cylinder and a piston therein, means providing a main combustion chamber and an auxiliary combustion chamber communicating with the main chamber, means to inject a jet of fuel across said main chamber toward said auxiliary chamber, said jet consisting of a spreading, highly atomized envelope and a coarsely atomized core, said main chamber containing relatively quiescent air and arranged to receive and permit the normal spreading of said highly atomized portion of the fuel within its quiescent air, and said auxiliary combustion chamber arranged to receive said core, the communication between said main chamber and said auxiliary chamber being such as to produce a swirl of air in said auxiliary chamber, the volumetric ratio of the main combustion chamber to the auxiliary combustion chamber being substantially equal to the ratio between the parts of the fuel received in the respective chambers.

2. In an internal combustion engine, a cylinder head adapted to overlie a cylinder in which a piston operates and having main and auxiliary combustion chambers, means to inject a jet of fuel across said main chamber toward said auxiliary chamber, said jet consisting of a spreading, highly atomized portion and a coarsely atomized core, said main combustion chamber containing relatively quiescent air and arranged to receive and permit the normal spreading of said highly atomized portion of the fuel within its quiescent air and proportioned to contain that portion of the air charge used in burning said highly atomized portion, and said auxiliary combustion chamber arranged to receive said core and proportioned to contain that portion of the air charge used in burning said core, and means to produce a swirl of air in said auxiliary combustion chamber.

ROBERT P. RAMSEY. 50
